UNITED STATES PATENT OFFICE.

HENRY J. SCHLOSS, OF NEW YORK, N. Y.

DESIGN FOR ORNAMENTATION OF BOYS' OVERCOATS.

SPECIFICATION forming part of Design No. 15,479, dated October 21, 1884.

Application filed July 24, 1884. Term of patent 3½ years.

To all whom it may concern:

Be it known that I, HENRY J. SCHLOSS, a citizen of the German Empire, residing at New York, in the county and State of New York, have originated and produced a new 5 Design for Ornamentation of Boys' Overcoats, of which the following is a specification.

This design is illustrated in the accompanying drawing, which shows a back view of the 10 overcoat.

In the drawing, the letter A designates the coat, and B is the cape, having a collar, C. From the lower edge of the collar extends a 15 strip, D, which is provided with a fold, d, while its lower edge a extends in a zigzag line

to the lower edge d of the cape. This strip D is further ornamented by a tassel, c.

What I claim as new, and desire to secure by Letters Patent, is—

The design for the ornamentation of a boy's 20 overcoat, said design consisting of a strip, D, the cape B, the fold d, and the zigzag edge a, as shown and described.

In testimony whereof I have hereunto set my hand and seal in the presence of two sub- 25 scribing witnesses.

HENRY J. SCHLOSS. [L. S.]
